CLAIM

The ornamental design for an industrial robot, as shown and described.

DESCRIPTION

FIG. 1 is a perspective view of a first embodiment of an industrial robot showing my new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof;

FIG. 8 is a front, top, and right side perspective view showing an arm of the article being stretched out;

FIG. 9 is a rear, top, and left side perspective view showing an arm of the article being stretched out;

FIG. 10 is a perspective view of a second embodiment of an industrial robot showing my new design;

FIG. 11 is a front view thereof;

FIG. 12 is a rear view thereof;

FIG. 13 is a top plan view thereof;

FIG. 14 is a bottom plan view thereof;

FIG. 15 is a right side view thereof;

FIG. 16 is a left side view thereof;

FIG. 17 is a front, top, and right side perspective view showing an arm of the article being stretched out;

FIG. 18 is a rear, top, and left side perspective view showing an arm of the article being stretched out;

FIG. 19 is a perspective view of a third embodiment of an industrial robot showing my new design;

FIG. 20 is a front view thereof;

FIG. 21 is a rear view thereof;

FIG. 22 is a top plan view thereof;

FIG. 23 is a bottom plan view thereof;

FIG. 24 is a right side view thereof;

FIG. 25 is a left side view thereof;

FIG. 26 is a front, top, and right side perspective view showing an arm of the article being stretched out; and,

FIG. 27 is a rear, top, and left side perspective view showing an arm of the article being stretched out.

(Continued)

The broken lines illustrate portions of the industrial robot that form no part of the claimed design.
